STEAM SEPARATOR

Palmer B. Place, Tenafly, N. J., assignor to Combustion Engineering Company, Inc., New York, N. Y., a corporation of Delaware

Application September 29, 1941, Serial No. 412,757

10 Claims. (Cl. 122—491)

This invention relates to the art of separating water from steam in a steam and water drum.

One of the primary objects of the invention is to make it possible to allow the concentration of dissolved salts and other impurities in the water of the boiler to very substantially increase over what is now standard practice, without encountering difficulties. Stated in another way, it is an object of the invention to make it possible to operate the boiler for longer periods of time before it becomes necessary to "blow down." Carry-over of foam is an important factor in this connection, and by my invention such carry-over of foam is substantially eliminated.

How the foregoing, together with such other objects and advantages as may be incident to the invention are realized, is illustrated in the accompanying drawings, wherein:

Figure 1 is a cross section through a boiler drum, illustrating in more or less diagrammatic form my improved means for accomplishing the objects of my invention;

Figure 2 is an enlarged cross section taken on the line 2—2 of Figure 1;

Figure 3 is a section taken on the line 3—3 of Figure 1; and

Figures 4, 5 and 6 are cross section corresponding to that of Figure 1 but illustrating various modifications of my invention.

Referring now to Figure 1, the reference character A denotes the drum, the normal water level in which is indicated at 7. At the upper portion, the drum is provided with steam outlet means such as a row of tubes 8. The number of rows of such tubes will vary with the particular installation. Leading from the drum are a plurality of downtake tubes 9. In this instance only one such row of tubes is shown, but it is to be understood that the number of rows will depend upon the particular installation.

A number of tubes 10 deliver a mixture of steam and water into the drum, above the normal water level thereof. Such tubes usually deliver a relatively high velocity mixture into the drum, as they lead from high steaming portions of the boiler such as boiler tubes and water walls subject to radiant heat. In this instance four rows of such tubes 10 are shown. Another row 10' of such tubes is shown delivering below the normal water level of the drum.

It is also to be understood that there may be a plurality of other tubes, likewise delivering into the drum below the normal water level thereof. These usually deliver from less highly steaming portions of the boiler.

Toward the right-hand side of the drum is a substantially upright partition or baffle 1, the lower portion of which depends below the normal water level of the drum and the upper portion of which rises thereabove.

Spaced apart from the partition 1, is a partition or baffle 2, the lower portion of which is substantially upright and depends below and rises somewhat above the normal water level of the drum. The upper portion of the baffle inclines upwardly toward baffle 1 to a point lying substantially in the plane of the upper end of baffle 1. The upper end of baffle 2, however, terminates at a point well removed from the upper end of partition 1.

A third partition 3 depends from the upper wall of the drum, from a point intermediate the tubes 8 and the uppermost row of tubes 10. This partition extends downwardly and terminates at a point spaced substantially above the upper end of partition 2.

It will be understood that partitions 1, 2 and 3 extend longitudinally of the drum and join with upright end plates 5, as shown in Figures 1 and 3. In Figure 3 but one such end plate is shown, but it will be understood that there is a similar end plate at the opposite end of the drum.

Associated with and supported by the partitions 1, 2 and 3 and the end plates 5, are a plurality of hoods 6, best shown in Figures 2 and 3. These hoods are open at their bottoms and at the left-hand ends thereof (looking at Figures 1 and 2), but closed at their right-hand ends. The hoods are of course closed at the top.

The hoods are spaced apart so as to provide channels 11 therebetween, best shown in Figures 2 and 3. These channels are closed at their ends and are open at their tops and bottoms. The group of hoods extends longitudinally of the drum.

The partitions 1, 2 and 3, the end plates 5, and the hoods coöperate with one another and with the water in the drum, to divide the interior of the drum, above the normal water level thereof, into three spaces, B, C, and D, which are non-communicating except as follows. The channels 11 afford the sole communication between spaces B and C; and the hoods afford the sole communication between spaces C and D.

The steam and water mixture of the tubes 10 delivers into the space B. (In this instance, partition 1 also segregates the delivery of the tubes 10' which ultimately joins with the delivery of the tubes 10.)

The operation is as follows. All of the steam

and water mixture entering space B flows from such space downwardly into the separation space C, through the channels 11, in the form of sheets or rectangular jets. These jets, on leaving the lower ends of the channels, fan or spread or bush laterally so as to merge with one another into a single sheet, preferably somewhat above the normal water level of the drum, as indicated in Figure 3. They also spread or fan or bush somewhat, in a direction longitudinally of the sheets. The combined area of the channels with relation to the combined area of the tubes whose delivery enters the space B, is such that the jets or sheets discharging downwardly through the channels, have substantial velocity. The steam and water mixture thus downwardly delivered into the separation space C impacts on the water in the drum. Some of the steam in the mixture may turn before impact upon the water; but the water of the mixture, being heavier, continues in its downward movement and joins with the water in the drum. Desirably the channels should have a cross-sectional area smaller than that of the hoods so that the jets have higher velocity than the steam leaving space C via the hoods. As illustrative, the hoods may be 2" in width and the channels 1" to 1½".

The only egress of steam from space C to space D being the hoods 6, it will be seen that the steam entering space C must leave by moving upwardly to the hoods.

In consequence of the foregoing, there is a separation of water from the steam, the great bulk of the water in the mixture delivered to the space C being therein separated from the steam. No appreciable amount of foam leaves the space. Foam entering into space B with the steam and water mixture, is apparently broken up in space C and joins the water in the drum, by virtue of the action of the sheets or jets delivered through the channels 11. Any foam which lies on the water in that portion of the space C which is to the left of the jets (Figure 1) does not find its way through the hoods into space D, despite the triangular spaces between the jets as they leave the channels. This is due to the following. The foam is heavier than steam and is not self-supporting. Hence it lies in a body on the water, as before mentioned. As is well known, the bubbles of foam adhere strongly to one another. For any appreciable amount of foam to leave through the triangular spaces, the body of foam would have to build up in height. This is prevented by the undercutting action of the jets and the steam thereof, which continually breaks up and destroys foam. The steam in space C to the left of the jets in all probability has a strong eddy flow induced by the action of the jets, and is in all probability entrained by the jets and is thereby largely freed of water, before ultimate escape through the hoods. There may be other reasons, but the fact is that the apparatus very effectively separates water with its impurities from the steam and prevents any substantial carry-over of foam, which is important.

For some installations no further separation of water from steam is required. For other installations it is desirable to provide a fourth longitudinally extending partition or baffle 4, extending downwardly from the upper portion of the drum wall, to a point spaced from partition 2 so as to provide a throat portion D' leading into the space D proper. This partition thus causes the steam entering from the hoods to take a tortuous path to the steam outlet means 8,

thus removing further quantities of water from the steam by virtue of change in direction of movement. In still other installations, it may be desirable to associate a drier 12 with the partition 4, in the portion D' of space D. In Figure 1, a conventional plate drier is shown. In all instances the primary and main separation occurs in space C.

In Figure 4 I have shown the application of my invention to another customary tube arrangement for drums. In this instance the drum has three rows of outlet tubes 8'; four rows of down-corner tubes 9'; seven rows of relatively high velocity tubes 10", of which four rows deliver below the normal water level, two rows above the normal water level, and one row at about the normal water level; and three rows of relatively low velocity tubes 10'''", which deliver below the normal water level.

The partition 1' in this instance rises from the lower portion of the drum wall at a point intermediate the tubes 10" and 10''", and extends upwardly to a point well above the normal water level of the drum. Partition 2' extends downwardly from the upper portion of the drum wall to the right of tubes 8', and rearwardly, the lower end thereof lying substantially in the plane of the upper end of partition 1 and well spaced therefrom. Partition 3' depends downwardly from the upper portion of the drum wall, at a point to the left of tubes 8', the lower end of such partition terminating well above the lower end of partition 2'. As before, spaced hoods and channels cooperate with partitions 1, 2 and 3 and the end plates to divide the interior of the drum above the normal water level into three spaces B, C, and D, which are non-communicating save as before described.

How the improvements are adapted to still other tube arrangements is shown in Figures 5 and 6, and no further description thereof is thought to be necessary other than to point out that where, as in the arrangement shown in Figure 4, there is no secondary separation means shown, in Figures 5 and 6 such secondary separation means is shown at 12'. It might also be mentioned that in some instances it is desirable to provide gathering or collecting boxes 13 where a single or several very large steam outlet pipe or pipes 8'' are provided, instead of a multiplicity of smaller tubes. In such arrangements the boxes 13 extend longitudinally of the drum, and communication between the same and the space D is provided by a plurality of openings 14.

I claim:

1. In combination in a steam and water drum having a plurality of inlet tubes, at least certain of which deliver a mixture of steam and water into the drum above the normal water level thereof, and having steam outlet means, a plurality of hoods located well above the normal water level and arranged side by side but in spaced relation with channels therebetween, and partition members cooperating with the hoods and the water in the drum to divide the interior of the drum above the water into three spaces, i. e., a space into which steam and water mixture is delivered by at least some of the inlet tubes, a steam separating space, and a space in communication with the outlet means, the said last three spaces being non-communicating save that the channels between the hoods afford communication between the said space into which mixture is delivered and the steam separating space and the hoods afford communication between the steam sepa-

rating space and the said third space which is in communication with the outlet means.

2. In combination in a steam and water drum having a plurality of inlet tubes, at least certain of which deliver a mixture of steam and water into the drum above the normal water level thereof, and having steam outlet means, a plurality of hoods located well above the normal water level and arranged side by side but in spaced relation with channels therebetween, and partition members cooperating with the hoods and the water in the drum to divide the interior of the drum above the water into three spaces, i. e., a space into which steam and water mixture is delivered by at least some of the inlet tubes, a steam separating space, and a space in communication with the outlet means, the said last three spaces being non-communicating save that the channels between the hoods afford communication between the said space into which mixture is delivered and the steam separating space and the hoods afford communication between the steam separating space and the said third space which is in communication with the outlet means, and the channels between hoods being substantially upright whereby the steam and water mixture is discharged into the separation space substantially vertically downward.

3. In combination in a steam and water drum having a plurality of inlet tubes, at least certain of which deliver a mixture of steam and water into the drum above the normal water level thereof, and having steam outlet means, a plurality of hoods located well above the normal water level and arranged side by side but in spaced relation with channels therebetween, and partition members cooperating with the hoods and the water in the drum to divide the interior of the drum above the water into three spaces, i. e., a space into which steam and water mixture is delivered by at least some of the inlet tubes, a steam separating space, and a space in communication with the outlet means, the said last three spaces being non-communicating save that the channels between the hoods afford communication between the said space into which mixture is delivered and the steam separating space and the hoods afford communication between the steam separating space and the said third space which is in communication with the outlet means, the channels between hoods being substantially upright whereby the steam and water mixture is discharged into the separation space substantially vertically downward, and the hoods being so spaced from one another and from the water in the drum that the downwardly directed sheets discharged by the channels merge into a continuous sheet, horizontally, at a plane above the normal water level.

4. In combination in a steam and water drum having a plurality of inlet tubes, at least certain of which deliver a mixture of steam and water into the drum above the normal water level thereof, and having steam outlet means, a plurality of hoods located well above the normal water level and arranged side by side but in spaced relation with channels therebetween, and partition members cooperating with the hoods and the water in the drum to divide the interior of the drum above the water into three spaces, i. e., a space into which steam and water mixture is delivered by at least some of the inlet tubes, a steam separating space, and a space in communication with the outlet means, the said last three spaces being non-communicating save that the channels be-

tween the hoods afford communication between the said space into which mixture is delivered and the steam separating space and the hoods afford communication between the steam separating space and the said third space which is in communication with the outlet means, and means in the space which is in communication with the outlet for effecting a final separation of water.

5. In combination in a steam and water drum having a plurality of inlet tubes, at least certain of which deliver a mixture of steam and water into the drum above the normal water level thereof, and having steam outlet means, a longitudinally extending group of alternating hoods and channels, the hoods being open at one end and closed at the other and the channels being open at each end; three longitudinally extending partitions and two end plates, cooperating with one another and with the hoods to divide the interior of the drum above the normal water level therein into three spaces, i. e., a space into which steam and water mixture enters, a separating space, and a space communicating with the outlet means, said spaces being non-communicating save that said channels afford communication between the said first space and the separating space, and said hoods afford communication between the separating space and the space in communication with the outlet means.

6. In combination in a steam and water drum having a plurality of inlet tubes, at least certain of which deliver a mixture of steam and water into the drum above the normal water level thereof, and having steam outlet means, a longitudinally extending group of alternating hoods and channels, the hoods being open at one end and closed at the other and the channels being open at each end; three longitudinally extending partitions and two end plates, cooperating with one another and with the hoods to divide the interior of the drum above the normal water level therein into three spaces, i. e., a space into which steam and water mixture enters, a separating space, and a space communicating with the outlet means, said spaces being non-communicating save that said channels afford communication between the said first space and the separating space, and said hoods afford communication between the separating space and the space in communication with the outlet means, said spaces being non-communicating save that said channels afford communication between the said first space and the separating space, and said hoods afford communication between the separating space and the space in communication with the outlet means, and a fourth longitudinally extending partition in the space last mentioned adapted to cause the steam flowing therethrough to change its direction of flow.

7. In combination in a steam and water drum having a plurality of inlet tubes, at least certain of which deliver a mixture of steam and water into the drum above the normal water level thereof, and having steam outlet means, a longitudinally extending group of alternating hoods and channels, the hoods being open at one end and closed at the other and the channels being open at each end; three longitudinally extending partitions and two end plates, cooperating with one another and with the hoods to divide the interior of the drum above the normal water level therein into three spaces, i. e., a space into which steam and water mixture enters, a separating space, and a space communicating with the outlet means, said spaces being non-communicating save that said channels afford communication between the said first space and the separating space, and said hoods afford communication between the separating space and the space in communication with the outlet means.

means, a fourth longitudinally extending partition in the space last mentioned adapted to cause the steam flowing therethrough to change its direction of flow, and a drier associated with said last mentioned partition in advance of the outlet means.

8. In a steam and water drum, having steam and water mixture inlet means and steam outlet means, the combination of a longitudinally extending group of alternating hoods and channels, and partitions cooperating therewith to divide the interior of the drum above the normal water level into three spaces, i. e., a space into which steam and water mixture enters, a separating space, and a space communicating with the outlet means, said spaces being non-communicating save that said channels afford communication between the first and second spaces, and said hoods afford communication between the second and third spaces.

9. In a steam and water drum, having steam and water mixture inlet means and steam outlet means, the combination of a longitudinally extending group of alternating hoods and channels, and partitions cooperating therewith to divide the interior of the drum above the normal water level into three spaces, i. e., a space into which steam and water mixture enters, a separating space, and a space communicating with the outlet means, said spaces being non-communicating save that said channels afford communication

between the first and second spaces, and said hoods afford communication between the second and third spaces, whereby steam and water mixture is discharged from said first space into the second space in the form of sheets, the channels being so located above the normal water level that the said sheets merge into a single sheet above the normal water level.

10. In a steam and water drum, having steam and water mixture inlet means and steam outlet means, the combination of a longitudinally extending group of alternating hoods and channels, and partitions cooperating therewith to divide the interior of the drum above the normal water level into three spaces, i. e., a space into which steam and water mixture enters, a separating space, and a space communicating with the outlet means, said spaces being non-communicating save that said channels afford communication between the first and second spaces, and said hoods afford communication between the second and third spaces, whereby steam and water mixture is discharged from said first space into the second space in the form of sheets, the channels being so located above the normal water level that the said sheets merge into a single sheet above the normal water level, the channels being narrower than the hoods whereby the velocity of flow through the channels is greater than that through the hoods.

PALMER B. PLACE.
